US00D603859S

(12) **United States Design Patent**
Webb, II et al.

(10) **Patent No.:** US D603,859 S
(45) **Date of Patent:** ** Nov. 10, 2009

(54) **MOBILE COMMUNICATION DEVICE
HOUSING**

(75) Inventors: **William D. Webb, II**, San Francisco, CA (US); **Jesse S. Madsen**, Oakland, CA (US)

(73) Assignee: **T-Mobile USA, Inc.**, Bellevue, WA (US)

(**) Term: **14 Years**

(21) Appl. No.: **29/334,270**

(22) Filed: **Mar. 23, 2009**

(51) **LOC (9) Cl.** 14-03

(52) **U.S. Cl.** D14/248

(58) **Field of Classification Search** ..... D14/138 R, D14/138 AD, 138 AC, 138 C, 138 G, 191, D14/203.1–203.8, 496, 138 AA, 138 AB, D14/247–248, 137, 147, 218, 341–347; D10/65, D10/78, 104; D13/168; D18/7; 455/566, 455/575.1, 575.3

(57) **CLAIM**

The ornamental design for an mobile communication device housing, as shown and described.

DESCRIPTION

FIG. 1 is a back perspective view of a mobile communication device housing showing our design; and,

FIG. 2 is a back view thereof.

The broken lines immediately adjacent the shaded areas represent the bounds of the claimed design while all other broken lines are directed to environment and are for illustrative purposes only; the broken lines form no part of the claimed design.
